DESIGN FOR A TANK VEHICLE

John F. Frazier, Detroit, Mich., assignor to Gar
Wood Industries, Inc., Detroit, Mich., a corporation of Michigan

Application May 22, 1936, Serial No. 62,776

Term of patent 7 years

To all whom it may concern:

Be it known that I, John F. Frazier, a citizen of the United States, residing in Detroit, in the county of Wayne, State of Michigan, have invented a new, original, and ornamental Design for a Tank Vehicle, of which the following is a specification, reference being had to the accompanying drawing, forming a part thereof, wherein:

Figure 1 is a side elevational view showing the tank vehicle embodying my new design;

Figure 2 is a front elevational view of a tank vehicle; and

Figure 3 is a rear elevational view thereof.

I claim:

The ornamental design for a tank vehicle substantially as shown.

JOHN F. FRAZIER.
